OTHER PUBLICATIONS

U.S. Appl. No. 13/742,544, filed Jan. 16, 2013, Bale.

Primary Examiner — Katrina A Betton(74) *Attorney, Agent, or Firm* — David S. Alavi(57) **CLAIM**

The ornamental design for a lockbox for a coupler of a trailer, as shown and described.

DESCRIPTION

FIG. 1 is a perspective view of a lockbox for a coupler of a trailer;

FIGS. 2-7 are top, left side, right side, bottom, front, and back views, respectively, of the lockbox.

FIG. 8 is an exploded perspective view of the lockbox.

FIG. 9 is a perspective view of a bottom assembly of the lockbox separated from a top cover of the lockbox;

FIGS. 10-15 are top, left side, right side, bottom, front, and back views, respectively, of the separate bottom assembly; and,

FIG. 16 is a perspective view of the top cover of the lockbox separated from the bottom assembly;

FIGS. 17-22 are back, front, left side, right side, top, and bottom views, respectively, of the separate top cover.
